(57) **CLAIM**

I claim the ornamental design of a rifle case, as shown and described.

DESCRIPTION

FIG. 1 is a front-top-right perspective view of the rifle case; FIG. 2 is a front elevational view of the rifle case of FIG. 1; FIG. 3 is a back elevational view of the rifle case of FIG. 1; FIG. 4 is a left-side elevational view of the rifle case of FIG. 1; FIG. 5 is a right-side elevational view of the rifle case of FIG. 1; FIG. 6 is a top elevational view of the rifle case of FIG. 1; and, FIG. 7 is a bottom elevational view of the rifle case of FIG. 1. The broken lines shown are included for the purpose of illustrating unclaimed subject matter and forms no part of the claimed design.
